UNITED STATES PATENT OFFICE.

EMILE TINTANNÉ, OF CAMAGUEY, CUBA.

GUIDING DEVICE.

1,293,248.

Specification of Letters Patent.

Patented Feb. 4, 1919.

Application filed June 5, 1918. Serial No. 238,325.

To all whom it may concern:

Be it known that I, EMILE TINTANNÉ, a citizen of the United States, residing at Camaguey, Republic of Cuba, have invented 5 certain new and useful Improvements in Guiding Devices, of which the following is a specification, reference being had to the accompanying drawings.

This invention relates to certain improvements in guiding devices and has relation more particularly to a device of this general character especially designed and adapted for use in connection with drafting work and more particularly in the formation of 15 script lettering and it is an object of the invention to provide a device of this general character having novel and improved means whereby it may be employed with equal facility in connection with vertical or inclined lettering in accordance with the requirements of practice.

It is also an object of the invention to provide a novel and improved device of this general character which is adapted to be 25 employed in connection with a T square or other instrument and which includes two relatively movable members whereby the device may be readily and conveniently employed in the production of vertical letters 30 or of letters arranged on differing inclines.

The invention consists in the details of construction and in the combination and arrangement of the several parts of my improved guiding device whereby certain important advantages are attained and the device rendered simpler, less expensive and otherwise more convenient and advantageous for use, as will be hereinafter more fully 45 set forth.

40 The novel features of my invention will hereinafter be definitely claimed.

In order that my invention may be the better understood, I will now proceed to describe the same with reference to the accompanying drawings, wherein:

Figure 1 is a view in top plan of a guiding device constructed in accordance with an embodiment of my invention; and

50 Fig. 2 is an enlarged fragmentary view partly in section and partly in elevation illustrating the pivotal connection between the swinging arm and the plate as herein disclosed.

As disclosed in the accompanying drawings P denotes a plate formed of transparent xylonite or other transparent material and which has produced therein a series of openings 1 oval in form and of differing sizes. By having the plate P of transparent material it will be at once self-evident that 55 said plate offers no visual obstruction to the work. The upper or outer face of the plate P is provided thereon with the markings 2 coacting with each of the openings 1 and defining the longitudinal and transverse 60 axes thereof so that the center of the opening may be readily determined by the eye and which is of especial importance when it is desired to produce ovals concentric to the oval defined by each of the several open- 65 ings 1.

The present guiding device is of especial advantage when used in connection with my improved scribe which is particularly described and claimed in my copending application executed on even date herewith, Serial 70 No. 238,324.

The plate P is oblong in form and secured to opposite extremities of a longitudinal marginal edge thereof are the oppositely 75 directed arms 3 held to the plate P through the medium of the coacting threaded pins 4 and nuts 5. The arms 3 are secured to the upper face of the plate P and pivotally engaged with the outer end portion of one of 80 the arms 3 is an elongated arm 6 arranged in the same plane as the plate P and having its longitudinal edges straight. Intermediate its length the arm 6 is provided with 85 an upstanding button 7 or the like whereby 90 the same may be conveniently manipulated during a working operation.

The arm 6 is of a length in excess of the length of the plate P and its free end portion is provided with the laterally directed 95 extension 8 also in the same plane as the plate P and which extends in a direction toward the plate but at a side thereof.

The extension 8 is provided with the arcuate slot 9 concentric to the pivot 10 of the 100 arm 6 and arranged along said slot 9 are the degree graduations 11 whereby the angle of inclination between the arms 6 and the longitudinal axis of the plate P may be determined.

105 The second arm 3 overlies the extension 8

and has disposed therethrough the holding screw 12 which is also directed through the slot 9. Coacting with the screw 12 is the binding nut 14.

5 In practice the outer longitudinal edge of the arm 6 is adapted to be brought in contact with a T square or other guide and when the plate P and arm 6 are in contact the openings 1 are in a position for use in connection 10 with vertical lettering. When it is desired to employ the guide in connection with inclined lettering the plate P and arm 7 are relatively moved to the desired degree as will be readily determined by the graduations 11.

15 As has been previously herein stated the guiding device as herein disclosed is particularly adapted for use in connection with my improved scribe described and claimed 20 in my co-pending application, Serial No. 238,234, and in practice the needle of such scribe is positioned at the center of the desired opening 1, and which center may be readily determined by the eye of a skilled 25 artisan in view of the markings 2 hereinbefore referred to.

As illustrated in Fig. 1, it is to be noted that the major axis of each of the openings 1 is substantially at right angles to the margin of the plate P with which the arm 6 co-acts.

From the foregoing description, it is thought to be obvious that a guiding device constructed in accordance with my invention 35 is particularly well adapted for use by reason of the convenience and facility with which it may be assembled and operated and it will also be obvious that my invention is susceptible of some change and modification 40 without departing from the principles and spirit thereof and for this reason I do not wish to be understood as limiting myself to the precise arrangement and formation of the several parts herein shown in carrying 45 out my invention in practice except as hereinafter claimed.

I claim:

1. A device of the character described comprising a plate provided with an opening, 50 an arm pivotally engaged at one end portion with the plate, and coacting means carried by the plate and the opposite end portion of the arm for holding the arm and plate at different relative angles, said plate having 55 markings on a face thereof radially to substantially the center of the opening.

2. A device of the character described comprising a plate provided with an opening, an arm pivotally engaged with the plate, the 60 longitudinal edges of the arm being straight, and coacting means carried by the plate and arm for holding the arm and plate at different relative angles, said plate having markings on a face thereof radially to substan-

tially the center of the opening, said arm and 65 plate being in the same plane.

3. A device of the character described comprising a plate provided with an opening, an arm pivotally engaged with the plate, and coacting means carried by the plate and arm 70 for holding the arm and plate at different relative angles, said plate having markings on a face thereof radially to substantially the center of the opening, the opening in the plate being oval in form, the arm coacting 75 with a marginal portion of the plate, the major axis of the opening being substantially at right angles to said margin of the plate.

4. A device of the character described comprising a plate having a straight edge and provided with an opening, an arm pivotally engaged at one end portion with an end portion of the plate adjacent the straight edge thereof, said arm being of a length to extend beyond the opposite end of the plate when the arm and plate are substantially in parallelism, the longitudinal edges of the arm being in parallelism, the opposite end portion of the arm being provided with an extension 80 disposed toward the plate but beyond the plate, and means coacting with the plate and extension of the arm for holding said plate and arm at different relative angles.

5. A device of the character described comprising a plate having a straight edge and provided with an opening, an arm pivotally engaged at one end portion with an end portion of the plate adjacent the straight edge thereof, said arm being of a length to extend 100 beyond the opposite end of the plate when the arm and plate are substantially in parallelism, the longitudinal edges of the arm being in parallelism, the opposite end portion of the arm being provided with an extension 105 disposed toward the plate but beyond the plate, and means coacting with the plate and extension of the arm for holding said plate and arm at different relative angles, said plate, arm, and extension being in substantially the same plane.

6. A device of the character described comprising a plate having a straight edge and provided with an opening, an arm pivotally engaged at one end portion with an end portion of the plate adjacent the straight edge thereof, said arm being of a length to extend beyond the opposite end of the plate when the arm and plate are substantially in parallelism, the longitudinal edges of the arm 120 being in parallelism, the opposite end portion of the arm being provided with an extension disposed toward the plate but beyond the plate, said extension being provided with an arcuate slot concentric to the pivot of the 125 arm, a second arm carried by the end of the plate adjacent the extension and overlying the extension, and a clamping member car-

ried by the second arm and disposed through the slot of the extension.

7. A device of the character described comprising a plate provided with an opening, 5 an arm pivotally engaged with the plate, and coacting means carried by the plate and arm for holding the arm and plate at different relative angles, said plate having markings on a face thereof radially to substan-

tially the center of the opening, the opening in the plate being oval in form.

In testimony whereof I hereunto affix my signature in the presence of two witnesses.

EMILE TINTANNÉ.
